AMMUNITION FEED BOOSTER

James E. Chapman, Los Angeles, and George A. Bussiere, Inglewood, Calif., assignors to North American Aviation, Inc., Inglewood, Calif., a corporation of Delaware

Application November 29, 1941, Serial No. 420,958

7 Claims. (Cl. 89—33)

1

The present invention relates generally to means or mechanism for boosting the feed of ammunition belts to machine guns, especially those guns for which it is highly desirable to store large quantities of ammunition at a point substantially remote from the guns, and has for its primary object the provision of a mechanism which may be readily regulated and adjusted so as to act solely in conjunction with the conventional ammunition feed of the gun in the ammunition feeding operations, to thus avoid all danger of overfeeding, and at the same time permit of manual feed of the ammunition belt at any time this becomes necessary or desirable.

It is well known that in the use of machine guns in airplanes it is desirable, on account of limited space immediately adjacent the gun, to feed thereto ammunition belts from a storage point some distance from the gun. It is also true that modern requirements for shells of increasing calibre have increased the weight of the ammunition belts and the difficulties in properly feeding the same, from a remote point of supply or storage, to the gun. These factors have resulted in over-taxing the conventional ammunition feed of the gun, and it is for this reason a major consideration of the present invention to provide an efficient means of boosting the feed of the ammunition at a point between ammunition storage and the conventional feeding mechanism at the gun, which will efficiently assist the latter in its feeding operations and effectively take care of the greater length of ammunition belts and their greater weight under modern demands.

A further object is the provision of an ammunition feed booster, of an electrically operated character in connection with means effective to synchronize the boosting impulses thereof with the feeding operations of the conventional ammunition feed at the gun.

A still further object is the provision of a booster unit which will be compact, of small size, and capable of ready use at any one point, or several points, in the line of ammunition feed to the gun.

With the foregoing in mind, the invention will be now described in detail in reference to the accompanying drawing, forming a part of this specification, and in which,

Fig. 1 is a side view, illustrating the practical application of the booster in connection with an ammunition belt.

Fig. 2 is a detail vertical longitudinal section

2 taken substantially centrally through the booster.

Fig. 3 is a diagram of the motor circuit of the booster controlled by the firing key operation of

5 the gun.

Referring now particularly to Figs. 1 and 2, the invention contemplates the provision of a booster unit in which a feed sprocket 10, for an ammunition belt A, which sprocket may be suitably mounted in the feed line of the belt between the gun and an ammunition storage station, has imparted thereto, rotatable step by step feed movements from a motor 11. This motor is shown encased within the sprocket, the latter being hollow for this purpose, and the motor being supported at one end in connection with an end plate 12.

The plate 12 closes one end of the sprocket 10 and may form part of any suitable support maintaining the unit as a whole in the desired position for use. Plate 12 may also support an adjustable member at 13 for adjusting the brushes of the motor 11 to control its power output. However, this may be accomplished by controlling a rheostat 44 through adjustable member 13, the object of such control being to so regulate the power output of the motor substantially below that required for ammunition feed so that it will function only in connection with the operation of the conventional ammunition feed of the gun.

The motor may support rollers 14 or other anti-friction members therearound for the spacing and rotatable support of the sprocket 10, and 35 drives the latter through reduction gears 15 at the opposite internally toothed end of the sprocket, and through a magnetically controlled clutch indicated at 16, so that when current is cut off from motor 11, the sprocket is permitted to free 40 wheel and allow manual manipulation or feed of the ammunition for any reason, as for instance failure of the gun to fire through a defective shell.

The last mentioned end of the sprocket 10 carries a closed end piece 17 which has rotatable bearings 18 in an end frame 19. This frame 19 and the first mentioned end plate 12 may cooperate to support a shield 20 along and spaced from the sprocket 10 to hold the ammunition belt A in properly meshed feeding relation with the sprocket, as best seen in Fig. 1.

The end plate 12 may have a socket 21 for reception of a current feed plug for supplying current to the motor, and the magnetic clutch 55 may include a stationary brake plate indicated

at 22 and a driving plate 40 connected to be driven by the motor 11, as suggested at 41. The clutch plate 16, which floats between the plates 22 and 40, is mounted on shaft 42 which also carries gear 43 of the reduction gearing 15. A spring 23 tends to move the shaft 42 to the left in Fig. 2, thus tending to disengage the driven plate 16 from the driving plate 40. A magnetic coil 46 is connected in parallel with the motor. When the coil 46 is energized, the magnetic current attracts the driving plate 40, thereby pulling the driven plate 16 from the brake plate 22 and against the driving plate 40. When the circuit is broken, the magnetic attraction ceases and the spring 23 is permitted to move the clutch plate 16 to a braking position against the brake plate 22 and the driving plate 40. The braking action stops rotation of the gearing 15 by stopping rotation of the meshing gear 43. The said braking mechanism tends to prevent rotation of the sprocket 10 when the motor circuit is broken. A hand piece 24 is provided at the outer end of the shaft 42, to manually shift the clutch plate 16 away from the brake plate 22 so that the sprocket 10 may free wheel.

According to the diagram of Fig. 3, closure of the firing switch 25 in the line 26 from a suitable source 27 of current and the firing solenoid of the gun, feeds current into the line 28 through the motor 11 to ground, to thus operate the booster motor.

In the motor line 28 of Fig. 3, there is shown a knock-out switch 32, which is normally closed in operation. This switch is shown in Fig. 1 as controlled by an arm 35 normally held, in a position to maintain the switch closed, by its contact with the ammunition belt A. When the end of the ammunition belt passes the switch 32, arm 35 drops and the switch opens to thus prevent further motor actuation of the sprocket. It is contemplated such a switch arrangement may be used at a point in the ammunition feed line, so that when it is opened there will remain only a portion of the ammunition belt that the conventional feed of the gun is well able to take care of without assistance by the booster. This arrangement obviously need not be used except where there is possibility of buckling of the ammunition belt.

The invention as shown and above described supplies a small, compact unit capable of installation in approximately the space normally occupied by the guide sprocket alone, as well as one which may be manufactured as a standard ammunition feed booster for all installations where such a booster may be needed.

While we have illustrated and described what we now regard as the preferred embodiment of our invention, the construction is, of course, subject to modifications without departing from the spirit and scope of our invention. We, therefore, do not wish to restrict ourselves to the particular form of construction illustrated and described, but desire to avail ourselves of all modifications that may fall within the scope of the appended claims.

Having thus described our invention, what we claim and desire to secure by Letters Patent is:

1. An ammunition feed booster for machine guns including a hollow sprocket, an electric motor within the hollow of the sprocket, a circuit for the motor, and a magnetic clutch also in the circuit and disposed to operatively connect the motor with the sprocket interiorly thereof upon closing of the circuit, and the clutch being con-

structed and arranged to resist rotation of the sprocket when the circuit is broken.

2. An ammunition feed booster for machine guns including a hollow sprocket, an electric motor within the hollow of the sprocket, gearing operatively connecting the motor with the sprocket, a brake means, a floating clutch plate having braking, neutral and motor-sprocket-connecting positions, spring means tending to move the clutch plate into engagement with the brake means for its braking position, a magnetic coil disposed when energized to move the clutch plate into its position of operatively connecting the motor with the sprocket against the action of the spring means, and means to move the clutch plate into its neutral position for disconnection from the sprocket and rotation of the sprocket independently thereof.

3. A feed booster unit for ammunition feed belts, including a hollow sprocket, a motor therein, reduction gearing connecting the motor in driving relation with the sprocket, a magnetic clutch between the motor and said gearing for connecting the motor and gearing when said clutch is energized, and an electric circuit including said motor and said magnetic clutch arranged for simultaneous operation thereof.

4. An ammunition feed booster for machine guns including a sprocket and an electric circuit comprising an electric motor and magnetic clutch means, said clutch means being positioned between the motor and the sprocket whereby to actuate the clutch to drive the sprocket when said circuit is energized.

5. An ammunition feed booster for machine guns including a sprocket and an electric circuit comprising an electric motor and magnetic clutch means, said clutch means being positioned between the motor and the sprocket whereby to actuate the clutch to drive the sprocket when said circuit is energized, said clutch means including a braking element for stopping rotation of the sprocket upon deenergization of the circuit, and means for manually releasing the braking element so as to permit free rotation of the sprocket while the motor is deenergized.

6. An ammunition feed booster for machine guns, comprising a hollow tubular sprocket, an electric motor within said sprocket and comprising bearings for said sprocket, a motor shaft having a driving clutch plate, reduction driving gearing arranged for driving said sprocket, a rotatable driving shaft for said gearing constructed and arranged for longitudinal displacement and having a driven clutch plate thereon engageable with the driving clutch plate, a fixed brake plate, means biasing said driven plate in engagement with said brake plate, a power circuit including said motor, and means operative when the circuit is energized to displace said driving shaft and driven plate out of engagement with the brake plate and into engagement with the driving plate.

7. In combination, a gun firing means, an ammunition feed booster including a sprocket, and an electric circuit comprising said gun firing means, an electric motor and magnetic clutch means, said clutch means being positioned between the motor and the sprocket, whereby said ammunition feed booster and the firing means are actuated during energization of the circuit.
